J. B. GROH

SIGN

Filed March 3, 1925

BY

B. J. Craig
INVENTOR.
J. B. GROH

ATTORNEY.

UNITED STATES PATENT OFFICE.

JACOB B. GROH, OF LOS ANGELES, CALIFORNIA, ASSIGNOR OF ONE-HALF TO JAMES H. GROH, OF OCEAN PARK, CALIFORNIA.

SIGN.

Application filed March 3, 1925. Serial No. 12,811.

This invention relates to signs.

The general object of the invention is to provide a sign which is constructed so that the entire sign is lighter in weight than the weight of the air it displaces so that the sign will be suspended in elevated position.

One of the specific objects of the invention is to provide a sign which may consist of one or more hollow characters made of light weight material and inflated with a light gas so that the sign will be maintained in elevated position.

Another object of the invention is to provide a sign wherein the characters are made from hollow tubes of flexible material filled with gas.

A further object of the invention is to provide a sign comprising a frame constructed of light material and having elongated rubber tubes therein formed to simulate characters and wherein the tubes are inflated to hold them in distended position.

Other objects of the invention will be apparent from the following description taken in connection with the accompanying drawings wherein Fig. 1 is an elevation of a sign embodying the features of my invention; Fig. 2 is a top plan view of the sign; Fig. 3 is a perspective view showing a modified means for supporting the sign; Fig. 4 is an elevation showing a further modified form of support and Fig. 5 is a top plan view of one of the elements of which the sign is constructed.

Referring to the drawings by reference characters, I have shown a sign embodying the features of my invention at 10. The sign may be constructed in any desired manner and in the following description although I refer to letters and numerals, I wish it to be understood that my invention may be embodied in various ways other than by letters and numerals, if desired. For instance, a character which is used as a trade mark may be employed as the figure of the sign.

Referring again to the drawings, it will be seen that the sign as shown comprises a frame 11 consisting of longitudinal members and transverse members. The frame as shown in Fig. 1 comprises an upper member and a lower member which may be sep-

arately made and may be united by fastening members 12.

The frames 11 are preferably made of 55 bamboo or other light wood or they may be made of aluminum or other light weight metal.

The frames comprise a polygonal body within which the characters 14 are secured. 60 Each of the characters as illustrated comprise a hollow tubular body preferably constructed of rubber or other material and having an inflating nipple 15 thereon.

Each character is made from one or more 65 of the tubular bodies 14 and these tubular bodies are held in the proper position to form the desired characters by means of strings 16 which are secured to the frame in a suitable manner to hold the characters 70 in their proper position.

In the sign I have shown the word Rogen as on the top line and beneath it the numerals 57 although any desired characters 75 may be used.

The bodies are preferably filled with hydrogen, helium, or other relatively light gas so that the whole framework will be suspended in the air.

I prefer to cover the sustaining tubular 80 bodies with phosphoric paint as shown at 18.

The sign may be held in position in any desired manner. In Fig. 1 it is shown as supported on a flag pole or other support 19 by means of a cord 20 which engages 85 an eye 21 on the sign.

In Fig. 3 the sign is supported at the bottom by cords 25, while the upper portion of the sign is held against undue swaying by cords 26. In Fig. 4 the sign is held 90 by a cord 27 which holds the sign in the manner similar to that in which a kite is held.

In addition to the fastening members 12 95 the ends may be braced by strips 30 if desired.

Having thus described my invention, I claim:

In a sign, a supporting member comprising a relatively light frame comprising longitudinal members and transverse members 100 united to and holding said longitudinal members in spaced apart relation, characters arranged within and upon said frame, said

2
characters being formed by hollow tubular bodies, said bodies containing a fluid of lighter than air density, said hollow tubular bodies when free from said frame being straight and means for forming said hollow tubular bodies into the form of said characters, said means comprising strings engag-

ing the normally straight hollow tubular bodies and attached to said frame in such a manner as to form said straight hollow ¹⁰ tubular bodies into the desired character.

In testimony whereof, I hereunto affix my signature.

JACOB B. GROH.
